UNITED STATES PATENT OFFICE.

EMERSON S. BROOKS, OF MORGANTOWN, NORTH CAROLINA.

RAILROAD CROSS-TIE.

1,227,036.

Specification of Letters Patent. Patented May 22, 1917.

Application filed September 7, 1916. Serial No. 118,886.

To all whom it may concern:

Be it known that I, EMERSON S. BROOKS, a citizen of the United States, residing at Morgantown, in the county of Burke and 5 State of North Carolina, have invented new and useful Improvements in Railroad Cross-Ties, of which the following is a specification.

This invention relates to improvements in 10 railroad cross ties, and one of its objects is to provide a combination cast or pressed metal and wood tie which embodies the strength, durability and final economy of a metallic body with the resiliency or cushioning action and spike holding properties 15 of a wooden base support, thus producing a tie which combines these and other substantial advantages in a unitary structure.

A further object of the invention is to 20 provide a tie consisting of a hollow metallic body inclosing at its ends wooden fillers which form backings for the rail supporting surfaces of the body, and in the production of which good portions of discarded wooden 25 ties and other refuse or cheap wood blocks may be employed with resultant economy, the casing being adapted for the use of ordinary spikes for securing the rails, which spikes are driven into the fillers so that the 30 superior holding qualities of spikes embedded in wood may be obtained, so that the use of bolts and nuts or other fastenings which are liable to work loose is avoided.

A still further object of the invention is 35 to provide a construction of metallic casing or tie body which is adapted to prevent shifting of the fillers and play and loosening of the spikes under certain strains upon the rails, which is constructed to receive a portion 40 of the ballasting material and to be firmly anchored therein, which is in the form of a solid casting so as to be devoid of all liability of the spreading of parts thereof, as is liable to happen with pressed or 45 stamped ties, which is constructed to permit drainage off of the water; and which is adapted for the ready and convenient removal of old wooden fillings and the insertion of new ones when required without re- 50 moval of the tie from the rail bed or otherwise disturbing its position.

A still further object of the invention is to provide a construction of metallic tie body or casing which will to a large measure 55 protect the wooden fillings from moisture, and which obviates the necessity of employ-

ing other fillings by so constructing the same as to receive a portion of the ballasting material, which may be readily and conveniently removed whenever it is desired to 50 remove the tie from the rail bed or to apply new fillers.

With these and other objects in view, the invention consists of the features of construction and combination and arrangement 65 of parts more fully described hereinafter, reference being had to the accompanying drawings, in which—

Figure 1 is a top plan view of a railtie embodying my invention and showing the 70 same in position in a road bed;

Fig. 2 is a vertical longitudinal section through the tie;

Fig. 3 is a central vertical section thereof;

Fig. 4 is a perspective view of the tie 75 body or casing with the fillers removed, parts being broken away to clearly show the internal construction;

Fig. 5 is a fragmentary longitudinal section showing a slightly modified form of 80 construction; and

Fig. 6 is a vertical transverse section through the form of tie shown in Fig. 5.

Referring to the drawings, 1 designates the body or casing of the tie which is of 85 oblong rectangular form and substantially box-shaped in cross section. This body or casing is formed of cast metal, preferably of cast or pressed steel, and comprises a bottom wall 2, side walls 3 and a top wall 90 composed of end sections 4, the top of the body or casing being entirely open between the inner edges of the wall sections 4 and from side to side thereof, as indicated at 5.

The bottom wall 2 and side walls 3 of 95 the body or casing are continuous from end to end of the tie, and form with the top wall sections 4 end chambers, casings or sockets 6 to receive fillers 7 which snugly fit therein, which fillers are composed of blocks 100 of a suitable hard and durable wood which may be treated or not with any suitable preservative substance, such as creosote, tar or zinc chlorid, as desired.

The fillers 7 underlie and form base supports for the top plates 4 which constitute seats for the base flanges of the rails 8, which rails are secured to the tie by means of spikes 9 of ordinary construction which are driven downward through openings 10 in 110 said plates 4 into the wooden fillers 7, whereby the rails are firmly and securely fastened

in position. It will be understood that the wooden fillers not only serve to fill and thereby strengthen and reinforce the portions of the tie on which the rails are laid but also provide a cushioning base giving a desired degree of resiliency, and further serve as anchors for the spikes whereby the firm holding qualities of spikes embedded in wood are obtained and the use of bolts and nuts or other fastening devices which are liable to work loose entirely avoided. The construction described also enables the usual tie plates to be dispensed with, but these may be employed and spiked to the ties with the rails if desired.

The space within the tie body or casing between the inner ends of the filler blocks 7 forms a chamber for the reception of a portion of the ballasting material 11, which serves to properly weight the tie and anchor it firmly in the road bed. By reason of the fact that the top opening 5 extends fully across the tie, it will be evident that the ballasting material may be readily and conveniently removed or otherwise filled into or removed from the tie, whereby the use of permanent fillings forming a part of the tie is dispensed with, providing a lighter tie for greater convenience in transportation and handling, while at the same time enabling the ordinary ballasting material to be employed at the time of use to fill the unoccupied portion of the tie body and anchor it securely in place in the road bed.

The filler chambers 6 are separated from the central ballast receiving chamber 11 by vertical transverse partitions 12 cast with the tie body and which serve to reinforce and strengthen the tie as a whole and further serve as abutments against which the inner ends of the fillers 7 bear to limit the inward movement of said fillers. By this means the fillers may be accurately positioned when inserted and held from inward shifting movements under certain outward pressures or strains upon the rails which are transferred to the spikes with a tendency to force the filler blocks inwardly and to cause play and loosening of the spikes, the filler blocks being thus fixed from such shifting movements and loosening of the spikes under the pressures or strains mentioned entirely avoided and prevented. These partitions 12 are provided with openings 13 through which the ends of the filler blocks 7 are exposed, thus allowing tools to be inserted through the opening 5, upon removal of a portion of the ballast, for the purpose of driving out a filler block which has decayed or otherwise become unfit for use, thus obviating the necessity of disturbing the tie in any manner for this purpose.

The lower portions of the partitions 12 furthermore serve in conjunction with the lower portions of the bottom and side walls

to form a drain basin at the bottom of the chamber 11 in which any moisture passing downward through the contained ballasting material or otherwise taken into the tie will be collected and allowed to drain out through drain openings 14 formed in the central portion of the bottom wall 2 and of which any desired number and arrangement may be employed. Preferably a number of drain openings are used and disposed centrally of the chamber, the bottom wall of which is curved or dished in a transverse direction to facilitate the flow of the moisture to the drainage openings. By means of this basin and the protection afforded by the partitions to the lower portions of the inner ends of the filler blocks, whereby the moisture is kept out of direct contact with the blocks, it will be evident that liability of rotting of the filler blocks will be reduced and the life and durability of said blocks prolonged.

In the modified form of my invention shown in Figs. 5 and 6, the partitions 12 are in the form of comparatively short vertical walls which extend upward from the tie bottom and across between the side walls of the tie body and are integral with the walls, the projections extending upward to a sufficient height to leave an opening above 95 for the exposure of the inner ends of the fillers for a driving out action, and also to form a collecting basin at the base of the chamber 11 as previously described with reference to the construction shown in Figs. 100 1 to 4, inclusive.

In the use of the tie, it will, of course, be understood that the filler blocks may be applied before or at the time of use, and that when the tie and rails are laid in position the spikes are driven in an obvious manner to fasten the rails in place, the tie being partially embedded in the road bed and also held down by the weight of the central filling of ballast, by means of which 110 the tie will be held in place in a firm and secure manner. The tie thus constructed and arranged will support the rails with a desired degree of resilient play under the weight of rolling stock, and owing to the 115 rigidity of construction of its walls will maintain its shape and the fixed relationship of its parts against all pressures and strains falling thereon from the rails. If it should be necessary at any time to remove 120 either one or both fillers, this may be done by simply withdrawing the spikes and then driving the fillers out by means of tools employed through the opening 5 and chamber 11, and new fillers may be thereupon inserted in their place, entirely without the necessity of removing or disturbing the position of the tie or of anything except a portion of the ballasting material contained in 125 the central chamber, the conveniences and 130

advantages of which will be readily understood. In making the wooden fillers 7 perfect portions of otherwise imperfect ties or other wood blocks of similar dimensions 5 may be employed, thus enabling waste material to be used with great economy. The tie being entirely rigid throughout when in use, except as to the slight resiliency afforded to the walls 4 by the wooden blocks, it 10 will be evident that the parts of the tie cannot become pressed out of shape or otherwise injured by the weight or pressure of rolling stock in such a way as to loosen the blocks and rail fastenings, as is liable 15 to occur with pressed or stamped ties having joints or composed of a plurality of sections.

I claim as my invention:

1. A railway tie comprising a hollow oblong rectangular body having a central chamber and end chambers, said central chamber being open at its top and in communication with the end chambers and said end chambers being provided with spike 20 receiving openings in their top walls, and wooden fillers within the end chambers arranged to be engaged by the spikes driven through said openings.

2. A railway tie comprising a hollow oblong rectangular body open at each end and having a central ballast receiving chamber and end filler receiving chambers, said central chamber being open at its top and said end chambers being provided with top walls 30 forming rail supporting seats and having spike receiving openings therein, said end chambers being in open communication at the top with the central chamber and separated at the bottom therefrom by vertical 35 transverse partitions forming abutment walls, and wooden fillers within the end chambers and abutting at their inner ends against said partitions.

3. A railway tie comprising a hollow oblong rectangular body open at each end and having a central ballast receiving chamber and end filler receiving chambers, said central chamber being open at its top and said end chambers being provided with top walls 45

forming rail supporting seats and having spike receiving openings therein, said end chambers being in open communication at the top with the central chamber and separated at the bottom therefrom by vertical 50 transverse partitions forming abutment walls, and a water collection basin at the base of said central chamber, the bottom wall of the said central chamber being provided with drain outlets for the discharge 55 of water from said basin, and wooden fillers within the end chambers and abutting at their inner ends against said partitions.

4. A railway tie comprising a cast hollow oblong rectangular body open at each end, said body comprising continuous bottom and side walls and having top wall sections at the ends thereof forming rail supports, said top wall sections being separated by an intermediate opening extending the full width of the tie, the said top plate sections forming with the adjacent portions of the walls of the body end receiving chambers, and partitions integral with the bottom and side walls of the body at the inner ends of said chambers and forming a central chamber 75 for the reception of ballasting material, said partitions being arranged to leave openings above the same at the inner ends of the end chambers, and filler blocks within the end chambers and abutting against said partitions and exposed in part within the central chamber.

5. A cast metal tie comprising a hollow oblong rectangular body having continuous bottom and side walls, end top wall sections 85 provided with spike openings and spaced to leave an intermediate opening at the center of the tie extending the full width thereof, and forming end chambers and a central chamber, and partitions between the central 90 and end chambers integral with and extending fully between the bottom and side walls of the tie body.

In testimony whereof I affix my signature in presence of a witness.

EMERSON S. BROOKS.
